UNITED STATES PATENT OFFICE

ESMOND PHILIP GOODWIN WRIGHT, OF ALDWYCH, LONDON, ENGLAND, ASSIGNOR TO
INTERNATIONAL STANDARD ELECTRIC CORPORATION, OF NEW YORK, N. Y.

AUTOMATIC TELEPHONE EXCHANGE SYSTEM

Application filed July 12, 1929, Serial No. 377,726, and in Great Britain September 13, 1928.

This invention relates to automatic or semi-automatic telephone exchange systems.

One of the objects of the invention is to provide a system in which all the switches used in the speaking route are single motion switches of the no-normal type. A further object of the invention is to reduce to a minimum the apparatus individual to the conversion switches and to locate as much of the controlling apparatus as possible in common circuits.

Referring to the drawings:—

The reference characters which designate the relays are arranged with a reference letter and a numeral (F/9).

The letter designates the relay and the numeral the sets of contacts on the relays. For illustration SA/2 means that relay SA has two sets of contacts. F/9 means relay F has 9 contacts. In referring to a relay the letter will be alone used. Relay F/9 in the description will be referred to as relay F and so on. The numeral simply shows the number of contacts operated by the relay.

Fig. 1 shows a preselector circuit comprising a primary finder LF1, a secondary finder LF2 and a distributor switch D.

Fig. 2 shows a selecting circuit at the first numerical switching stage. A first conversation group finder is indicated above the broken line whilst below this line is illustrated a control circuit common to a group of finder switches. The control circuit comprises a control switch R1, a bye-pass switch R2 and an associated group of relays. The control switch R1 is equipped with wipers and banks 2 to 8 whilst the bye-pass switch R2 is equipped with wipers and banks C12, M12, M22, T12, T22, -1, -2, +1, +2, N21 and N22. Certain groups of positions of the switch R1 are used for effecting a marking in the bank of the bye-pass switch R2, contacts in the bank 7 in these positions being suitably strapped to the terminals in the control bank C12 of the switch R2, whilst other groups of positions are used for operatively connecting the control circuit with a particular finder switch over the banks 2, 4, 5, 6, and 7. Bye-pass conductors extend from the terminals of the banks -1, -2, +1, +2 of

the switch R2 to control circuits at the succeeding switching stage, and bye-pass test wires extend from the terminals of the banks T1, T2 to finder switches at the succeeding switching stage. The terminals in the marking banks M12, M22 are multiplied to corresponding terminals in the marking banks M of all the finder switches served by the control circuit. The control circuit as shown is arranged to absorb a first digit 6. Such a provision is desirable in circumstances well-known in the art and which it has not been thought necessary to enter into. For the purpose of this provision, however, two groups of terminals of the bank 7 of the switch R1 are strapped to the terminals of the control bank C12. Normally the first group is used for marking in the bank C, but if the digit 6 which is to be absorbed is dialled the switch R1 advances to the beginning of the second group of terminals without making an effective marking, but in response to a further digit a marking is effected over a selected terminal of the second group.

Fig. 3 shows a selecting circuit at the second switching stage. A second group finder is shown above the broken line, whilst below this line is indicated a control circuit comprising a control switch R1 equipped with wipers and banks 1, 2, 4, 5, 6, 7, 8, 9 and 10 and a bye-pass switch R2 equipped with wipers and banks C13, M23, M13, T23, T13, +2, +1, -2, -1 and N2. The banks of these switches are arranged similarly to those of the switches R1, R2 of the control circuit illustrated in Fig. 2 with the exception that the digit absorbing feature is omitted.

Fig. 4 shows a selecting circuit at the third or penultimate switching stage. A penultimate group finder is indicated above the broken line and below this line is shown a control circuit comprising a control switch R1 equipped with wipers and banks 1, 2, 4, 5, 6, 7, 8, 9 and 10 and a bye-pass switch R2 with wipers and banks C14, M24, M14, OM, T24, T14, -2, -1, N21 and N22. At this switching stage single bye-pass conductors only extend to control circuits at the final switching stage. The banks of the switches R1, R2 are arranged in similar fashion to those of the

corresponding switches in Figs. 2 and 3. The terminals of the bank OM are connected to overflow metering devices.

Fig. 5 shows a final selecting circuit. A final finder is indicated above the broken line and below this line is shown a control circuit comprising a control switch R1 with wipers and banks 1—9, and a bye-pass switch R2 with wipers and banks X2, X1, M25, M15, T25, T15, C15 and N2. Terminals of the banks 70 5, 7, 8, 9 in certain positions of the switch R1 are used for control purposes, whilst terminals of the banks 1, 2, 3, 4, 5 and 9 in other positions are used for associating the control circuit with a particular final finder. Banks 15 X1, X2 of the switch R2 are used for P. B. X. discrimination. Terminals in the banks T15, T25 are multiplied to corresponding terminals in the finder banks H and terminals in 20 the banks M15, M25 to corresponding terminals in the finder banks M.

Fig. 6 shows a modified form of selector circuit adapted to give access to 200 lines and illustrates above the broken line a conversation 25 selector circuit comprising two associated single-motion non-homing finder switches A6 and B6. The switch A6 is equipped with wipers -A, +A, HA, MA and the switch B6 with wipers -B, +B, HB, MB. Below the broken line is shown a control circuit common to a group of conversation selector circuits and comprising three switches, a switch R1 the banks of which are indicated 1—10, a switch R2 the banks of which are indicated 30 1—10, a switch R3 the banks of which are indicated AC, AM2, AM1, AT2, AT1, A+2, A+1, A-2 and A-1, and a switch R4 the banks of which are indicated BC, BM2, BM1, BT2, BT1, B+2, B+1, B-2 and B-1. The switches R2 and R3 are each equipped 35 with two sets of wipers. Access is had to bye-pass conductors extending to the next switching stage over banks AT2, AT1, A+2, A+1, A-2, A-1 of the switch R2 and over banks BT2, BT1, B+2, B+1, B-2, B-1 of the 40 switch R3.

Fig. 6a, is a diagram showing the arrangement of the marking wires between the control switches R2, R3 and the conversation switches A6, B6. Marking wires extend 45 from the banks BM2, BM1 to the control bank MB of the switch B6 and from the banks AM2, AM1 to the control bank of the switch A6. Group marking wires also extend from the first positions in the bank of the switch R1 to the control banks AC and BC of the switches R2 and R3, respectively. The later positions of the switch R1 are used 55 for operatively connecting the control circuit to any one of its associated conversation selector circuits over the banks 1 to 10.

Fig. 7 illustrates a method whereby a group of conversation switches may be switched from a faulty control circuit to an adjacent control circuit which normally serves a different group of conversation switches.

Fig. 8 is a schematic diagram illustrating the general layout of a typical system.

The finder switches comprise 100 point single motion step-by-step switches of the no-normal type having two sets of wipers arranged 180° apart each wiping an arc of 50 contact sets during one complete revolution of the switch shaft.

The switches R1 are 50-point step-by-step single motion switches. As in some cases less than half of the number of positions in the bank of R1 is required for marking purposes and for connecting the control circuit to the associated selector switches, the bank may have a second normal position, and have two corresponding groups of positions in the first and second halves of the bank, corresponding contacts being connected in parallel for the same marking or connecting function.

If the capacity of the R1 switch permits it a further similar group or groups of marking and connecting positions may be provided around the bank.

The switches R2 comprise 100 point single motion step-by-step switches having two sets of wipers arranged to wipe simultaneously over corresponding sets of bank levels.

The references used for referring to the various switches have for convenience been attached in the drawings to the stepping magnets of the corresponding switches.

A brief general indication of the operation of the system will now be given with reference to Fig. 8.

A calling subscriber S becomes connected over a line circuit LC and first and second line finders LF1, LF2 controlled by a distributor D to a free first group finder S associated with an idle control circuit C. The first digit dialled sets the control switch R1 which marks the wanted group in the bank of the bye-pass switch R2, which commences to advance immediately the impulses start arriving. The bye-pass switch R2 searches for an idle second group finder S1 having an idle associated control circuit C1 and at the same time the switch R1 hunts for the first group finder S which is to replace the bye-pass. The group finder S is then set on the trunk selected by the bye-pass switch R2. Meanwhile a second digit is passing over the bye-pass switch R2 to the control circuit C1 at the second switching stage, which operates in similar manner to the first stage selecting circuit. The control circuit C at the first stage is released when the control circuit C1 at the second stage has become operatively connected to the predetermined finder switch S1 over the wipers of the R1 switch at that stage. The finder switch S1 is then advanced to the trunk selected by the R2 switch associated with the control circuit C1. In a similar manner the connection is extended over a third group finder S2 to a final select- 130

ing stage under the control of a control circuit C2. At the final selecting stage the R1 switch of the selected control circuit C3 responds to the tens and units digits and marks 5 a wanted line S4 in the bank of the R2 switch. When the wanted line is engaged by the R2 switch, the R1 switch associates the control circuit C3 with the selected final finder S3 and a test is made of the condition of the wanted 10 line in the control circuit C3. If the wanted line is busy, a busy signal is given, whilst if the line is idle the finder S3 is advanced to it and ringing current is applied. The control circuit C2 is released when the R1 15 switch of the control circuit C3 has picked up the final finder S3. The release of the control circuit C2 brings about the release of the control circuit C3.

Referring now to Fig. 1 of the drawings a 20 subscriber's line terminates at the exchange in the banks of primary finders, such as LF1, and also in the banks of the connector switches, which are not shown. The subscriber's lines are formed into groups, and 25 there may be as many lines in a group as there are sets of contacts in the banks of the finders LF1, say 100, there being a sufficient number of finders provided for each group of lines to handle the traffic from that group. For each 30 group of subscribers' lines a common start relay SA is provided.

The secondary finders LF2 are linked to first group finders and are divided into 35 groups of sufficient size to handle the traffic which will be directed through them. Each of these groups of secondary finders is arranged to search for a different primary finder in each of the primary groups. Associated with each group of secondary finders is an 40 allotting and controlling switch D which pre-selects an idle secondary finder linked with an idle first group finder the control circuit associated with which also is idle. Preferably therefore the number of allotting switches D is equal to the number of groups of secondary finders and to the number of 45 primary finders in each group.

When a subscriber calls, a starting relay SA common to the subscriber's group marks 50 all the primary finders LF1 serving this group and starts a set of secondary finders LF2 preselected by the allotting switches D. These secondary finders LF2 hunt until two have reached marked primary finders LF1 and the two engaged primary finders then 55 hunt until one finds the calling line.

As an example, the originating traffic is 60 assumed to be sufficient to necessitate 12 primary finders per group, and in consequence there are provided 12 allotting switches and 12 groups of secondary finders. The first group of secondary finders will have access to the first primary finders of each group of primary finders, the second group of secondary finders will have access to the second

primary finders of each group of primary finders and so on to the twelfth group of secondary finders which will have access to the twelfth primary finder in each primary group. With this arrangement it will be seen that 70 the tracing back of calls from the first selector to the calling line is a simple matter, as the positioning of the secondary finder will indicate the primary group and the secondary group number will indicate the primary 75 switch in use in that primary group. The positioning of the primary switch in use will indicate the subscriber's line to which the first selector is connected.

A call will now be followed through in 80 greater detail with reference to Figures 1 to 5 of the drawings.

When a call is originated the line relay L is energized over the calling subscriber's loop, causing the line to test busy to the final 85 switches and placing a selectable potential on the test terminal H in the banks of the primary finders LF1 via both windings of the cut-off relay KA and contacts L2 operated. Relay L also closes a circuit for the common 90 group relay SA which closes a circuit via SA2, HA2, F1, K1 for the start relay J of all the idle distributor switches D and places a potential via the windings of relay HA and contacts SA1 on the marking contact C of all 95 the primary finders such as LF1 serving the line group to which the calling line belongs.

Relay J of each distributor switch D completes the following circuit:—contacts B2, J3, winding of relay H, distributor wiper DT, 100 wire T, contacts HS2, Figure 2, B2, P1, Q1, E10, wipers of switches R1 and R2 in their home positions, contacts B7 to battery.

Relay H closes a circuit via E1, F8, K7, H3 wiper F21 and interrupter springs of a switch 105 magnet (similarly designated in other parts of the drawings) for the stepping magnet F22 of the associated secondary finder LF2. At the same time a circuit is prepared for the test relay E over contacts H1, K5, wiper F2T 110 of the distributor switch D and wiper C of the secondary finder LF2. A spark quenching condenser is connected to the magnet F22 over wiper SQ2.

The secondary finder LF2 steps until it 115 reaches a marked primary finder LF1 thereby causing the response of relay E which opens the circuit of the driving magnet F22 at contacts E1 and closes at E2 a circuit via HE2 for relay F which locks via contacts F9, 120 J2 and prepares a circuit for test relay B at contacts F4.

The relay HA will not operate in series with a single relay E, but when a secondary finder controlled from another distributor 125 switch also engages a marked primary finder there will be two E relays in parallel and relay HA will operate and open at contacts HA1 the circuit to the marking contacts via its non-inductive winding and battery there- 130

by preventing other E relays from operating.

If a primary finder be already engaged when a secondary finder passes on to it, a relay HE is energized over contacts K6, H2, distributor wiper MN, wiper and multiple contact L of the secondary finder LF2, multiple contact such as L and wiper of the secondary finder already engaging the primary finder, front contacts such as KS1 or HS1 of the attaching or switching relay KS or HS, Fig. 2 of the group finder of the engaging secondary finder link, and the grounded hold wire H. Relay HE operates and at contacts HE2 holds open the circuit of relay F and closes an alternative circuit for the stepping magnet F22 independent of relay E, so that the secondary finder continues to advance. A primary finder will be taken into use, however, if it is idle, even if it is standing on a busy line since in this case the multiple L will not be grounded.

It will be seen that the secondary finders continue to hunt until two have seized primary finders of the group to which the calling party belongs.

When relay HA operates it opens at contacts HA2 the starting circuit of the J relays of the various distributor switches but by this time relays J of the distributor switches associated with secondary finders which have seized marked primary finders have been held energized via contacts K1 and F1.

The operation of relay F also completes a circuit for the stepping magnet F11 of the primary finder LF1 via contacts B1, F2, distributor wiper F12 and finder wiper R. The common spark quenching condenser is now connected to the magnet F22 via contacts F7 and wipers SQ1, SQ. When a primary finder engages the calling line relay B is energized via contacts F4, wiper F1T of the distributor switch D, wipers H of the secondary and primary finders, and the subscriber's cut-off relay KA.

Relay B locks up over contacts F5, B1 and at contacts B2 opens the circuit of relay H. Relay B also opens the circuit of the stepping magnet F11 at contacts B1 and closes a circuit via contacts B1, F6 for relay K which at contacts K1 opens the circuit of relay J, and at contacts K5 opens the circuit of relay E. Relay F now relapses and opens the circuit of relay B at contacts F5. On the relapse of relay F relay K locks over the make before break contacts F6 and contacts K3, H1.

A circuit is now completed from ground at contacts H1, F3, K2, interrupter contacts and magnet D of the distributor switch which rotates to find an idle secondary link the associated finder and its control circuit of which are also idle. When this occurs relay H energizes over contacts B2, K9, wiper DT and

the test wire T, and at contacts H1 opens the stepping circuit and unlocks relay K which in turn de-energizes relay H.

Should the distributor switch engage a secondary link which although idle has been pre-selected by another distributor switch, the relay HE is energized over contacts K6 the wiper CM, multiple contact, wiper such as CM of the other distributor to ground at contacts such as K4. An alternative ground is thereby provided for the relay K and magnet D via contacts K4, HE1 and the distributor switch continues to step in spite of the momentary response of relay HE.

It will be evident that if only one marked primary finder be idle this will hunt alone for the calling line. It is also possible for the calling line to have been picked up by a primary finder before a second starts its hunting operation.

As already described when a distributor is seized the selector circuit with its associated control circuit preselected thereby is tested over the wire T, contacts HS2, B2, P1, Q1, E10, the wiper and home contact of the bank 7 of the switch R1, the home contact and wiper of bank C12 of the switch R2, B7 to protective resistance and battery in order to determine if the control circuit is still idle. If the circuit is found to be free by the distributor circuit that circuit will reduce the potential on the common point between HS2 and B2 and consequently cause the control circuit to test busy.

When the preselector circuit has completed connection to the calling subscriber, a ground potential will be placed on the wire K causing the operation of relay KS. A circuit is now completed for relay A from battery and one winding of relay A, H3, KS2, negative wire, subscriber's loop, positive wire KS3, H5, second winding of relay A to ground. Relay A completes the obvious circuit for relay B over A2 and relay B opens the testing circuit at B2 and closes a locking circuit for KS through B3 and KS5. B7 opens the circuit to the battery and energizes the relay M. At the first interruption relay A releases but relay B being of the slow release type remains operated and completes a circuit for the magnet R1 through E4, B5, winding of relay C and A1 to ground. At the end of the interruption relay A reoperates and the switch R1 steps into position 2. In position 2 the circuit of relay M is opened and when relay M releases a circuit is completed for the magnet R2 through H8, interrupted springs, M1, wiper and home position of the bank N21 of switch R2, C2, Q1, P1, B3 to ground. The switch R2 takes a step and continues stepping by means of its own interrupter springs and the off normal contacts of the bank N21 to ground at E6 until relay M reoperates. The switch R1 takes one step for each impulse received from the subscriber's dial and the strapping between the banks

7 and C12 is so arranged that the circuit for relay M is completed whenever the R2 switch reaches the commencement of the group corresponding to that on which the R1 switch is standing. When the digit is completed relay C will release after a period and when relay M operates due to the switch R2 having reached the position indicated by the bank 7, relay M will reoperate, as already described. and a circuit will then be completed for relay E from battery and winding of relay E, G4, W6, C1, W4, M2, wiper and off normal contacts of the bank N21, E6 to ground. Relay E closes its light spring contact E9 and locks over its second winding to ground at B3. E10 opens the circuit for relay M which releases and recloses the driving circuit of the R2 switch through M1, wiper and off normal contacts of the bank N21, E5, Q1, P1 to ground at B3. Contacts E12 and E13 close the testing circuit for relays P and Q respectively and one or both of these relays will operate if the outlets on which the wipers are resting are free. If relay P alone operates the driving circuit of the switch will be opened at P1 and at P2 a circuit will be closed for relay H which will lock up via H6 to ground at B3. If relay Q operates the driving circuit of the switch will be opened at Q1, and at Q2 a circuit will be closed for relay J which will operate and close at J1 a circuit for relay H which will also operate. H6 will provide a locking circuit for both the relays H and J. If all the outlets of the group are engaged, the switch R2 will step eventually to the last contacts of the group in which position a circuit will be closed for the relay M through H10, B8, wiper and bank contact C12, E11, Q1, P1 and B3 to ground. Relay M will open the driving circuit of the switch R2 at M1, and close at M2 a circuit for relay G through E8. Relay G is of the slow to operate type and will not operate during the period when both relays E and M are operated during the initial operation of the former. However, on the last contacts of the group the circuit for relay G is maintained and this relay will eventually operate and connect at G7 the busy tone to the calling subscriber from lead BT.

When relay E operated a circuit was completed for the switch R1 through E3, the interrupter springs, and T1 to ground. This will cause the R1 switch to continue stepping until the relay T operates through wiper and bank contact 2, contacts KS5 to ground at B3. It will be understood that there is only one group finder accessible to this control switch with its relay KS operated. When both the relays T and H are operated due to the fact that the R2 switch has found a free outlet in the required group and the R1 switch has found the finder which it has been predetermined will complete the call, a circuit is completed for the finder magnet S through bank

contact and wiper 5 of switch R1, M3, H9 and T2 and at the same time a ground is extended through T3, the wiper and bank contact 7, to the finder wiper M and when the finder wipers stand on the outlet corresponding to that on which the switch R2 has switched through, the ground on the finder wiper M will be extended to the control wiper M12 or M22, J4 or J5, H11 to relay M. The operation of M opens the circuit for the finder magnet S at M3 and closes the circuit for the relay G by E8, M2, the off normal bank N21, E5, Q1, P1 to the ground on the test wire. Relay G will operate and close the circuit for relay HS through bank contact and wiper 4, G1, M4, H9 and T2 to ground. HS will operate and HS6 will extend ground over the H wiper to the H wire of the succeeding finder in order to mark that switch to the succeeding control. Contacts HS3 and HS4 will prepare the permanent circuit to replace the bye-path. HS5 grounds the H wire to hold the cut-off relay independently of the control circuit. The control circuit does not release until the ground potential is removed from the T12 or T22 wire by the succeeding control circuit. When the relay H operated the circuit for relay A was opened and relay B released also after a short period. Relays E, KS and T where maintained, however, by the ground potential on the test wire, which is maintained by the succeeding control circuit under the control of the calling subscriber's loop. When the succeeding finder removes ground from the T wire, relays T, KS and E, M and H release. When relay H releases, the homing circuit for the switch R1 is completed through E4, B4, H7, off normal contacts and wiper of bank 3, interrupter springs T1, to ground. In a similar way the homing circuit for the switch R2 is completed through H8, M1, wiper and off normal contacts N21, E6, to ground. When both these switches have returned to their home positions, the battery is reconnected to the test wire through B7. Should it happen that the subscriber dials a predetermined digit which the control circuit has been arranged to absorb, the switch R1 will come to rest in a position similar to position 6 in the drawings. A circuit is completed for relay W from battery and winding of relay W, wiper and bank contact of bank 8 of the switch R1, B3 to ground. Relay W will operate and lock through W7, C1 and W5 to ground. At W8 a particular contact is earthed in the control bank C12, whereby when the bye-pass switch reaches this position relay M is energized and arrests this switch until the next digit is dialled. At the same time a circuit is completed for the magnet R1 through C4, W2, the bank contact and wiper of the bank 3, the interrupter springs and T1 to ground, causing the switch R1 to step forward until it reaches the first contact connected to W1 where its circuit is

opened. The wiring of the bank 3 is so arranged that the R1 switch will step automatically to the 11th position in readiness for the second set of impulses. When the second set of impulses commences relay C operates, as already described, and the circuit for relay W is opened causing this relay to release. The subsequent operation of relays E, P or Q, H and T will take place, as already described.

Should it happen that the subscriber fails to dial, a circuit will be completed from the pulse lead A through the home contact and wiper of the bank 6, G3, B6, B7 to the relay G which will lock up over G2, C3 and B3 to ground. After some predetermined period a second pulse will be received over the pulse wire B, wiper and home contact of bank N22 of the R2 switch, G5 to relay E. Relay E on operating will lock through E9 to ground at B3 and open the circuit for relay G at E7. Relay P will operate from ground at B3 through G9, H13, E12, wiper and home contact of the T12 bank to protective resistance and battery. Relay P will cause the operation of relay H and the subscriber's loop will be switched via H2 and H4, J6 and J8 through the home contacts of the banks -1 and +1, G8 and E2, back to the relay A. When relay E operated, it closed the driving circuit of the magnet R1, as already described and this switch will step forward until relay T operates. Relay T will close a circuit, as already described, for the finder magnet S. When the finder has been driven to the terminals corresponding to those on which the switch R2 is standing (i. e. its home terminals), relay M will operate and a circuit will be closed for relay G through E8, M2, wiper and home contact of the bank N21, M4, H9 and T2 to ground. G1 closes a circuit for the relay HS which is maintained through HS6, H wiper and home contact of the finder S, home contact and negative wiper, HS3, subscriber's loop, HS4, positive wiper and home contact, to ground. The operation of G6 opens the circuit for relay A which releases and opens the circuit for relay B. Relay B in turn opens the circuit for relays E, G, H and T causing the switch R1 to return to normal. The finder relay HS is maintained operated over the subscriber's loop until the subscriber releases. The same operations occur if the subscriber fails to dial a second digit after the switch R1 has gone to its 11th position after responding to the digit 6.

When the control circuit is first seized a dialling tone if required is introduced through E1 to the winding of relay A. When the relay E operates the dialling tone is removed.

Referring now to Fig. 3 this selector circuit with its associated control circuit is tested through the wire T, contacts HS1, TT3, TT6, P1, Q1, E11, the wiper and home contact of bank 9, of switch R1 the home contact and wiper of bank C13 of switch R2 B5, to resistance and battery. If this resistance is connected to the test wire, the previous control circuit will switch through extending the subscriber's loop to conductors + and - thereby, causing the operation of relay A through H2, H4. Relay A closes the obvious circuit for relay B through A2. Relay B places ground on the test wire at B1 and removes the battery from the test wire at B5. At B6 a circuit is closed for relay M from battery and winding of relay M, H14, B6, wiper and home contact of the bank C13, home contact and wiper of the bank 9, E11, Q1, P1, TT6, B1, to ground. At the first impulse, relay A releases but relay B being of the slow release type, remains operated and completes a circuit for the magnet R1 through E3, B2, winding of relay C and A1 to ground. At the end of the impulse relay A reoperates and the switch R1 steps into position 2. In position 2 the circuit for relay M is opened by the wiper 9 and when M releases a circuit is completed for the magnet R2, through its interrupter springs, H7, M1, wiper and home position of the bank N2 of switch R2, C1 of B1, to ground. The switch R2 takes a step and continues stepping by means of its own interrupter springs and the off normal contacts of the bank N2, to ground at E5 until relay M reoperates. The switch R1 takes one step for each impulse received from the subscriber's dial and the strapping between the banks 9 and C13 is so arranged that the circuit for M is completed whenever the R2 switch reaches the commencement of the group corresponding to that on which the R1 switch is standing. When the digit is completed, relay C will release after a period and when relay M operates due to the switch R2 having reached the position indicated by the bank 9, relay M will operate as already described and a circuit will then be completed for relay E from battery and winding of relay E, G3, C3, M2, wiper and off normal contacts of the bank N2, E5, to ground. Relay E will close its light spring contact E10, and lock over its second winding to ground at B1. E11 opens the circuit for relay M which releases and recloses the driving circuit of the R2 switch through H7, M1, wiper and off normal contacts of the bank N2, E4, Q1, P1, TT6, to ground at B1. Contacts E13 and E14 close the testing circuits for relays Q and P respectively, and one or both of these relays will operate if the outlets on which the wipers are resting are free. If relay P alone operates the driving circuit of the switch will be opened at P1 and at P2 a circuit will be closed for relay H which will lock up via H5 through TT6 to ground at B1. If relay Q operates a driving circuit of the switch will

be opened at Q1, and at Q2 a circuit will be closed for relay J which will operate and close at J1 a circuit for relay H which will also operate. H5 will provide a locking circuit for both the relays H and J. The proper wiper set will be connected up at contacts J4-J8. If all the outlets of the group are engaged, the switch R2 will step eventually to the last contact of the group, in which position a circuit will be closed for the relay M through H14, B6, wiper and bank contacts C13, E12, Q1, P1, TT6, and B1 to ground. Relay M will open the driving circuit of the switch R2 at M1, and close at M2 a circuit for relay G through E7. Relay G is of the slow to operate type and will not operate during the period when both relays E and M are operated during the initial operation of the former. However, on the last contacts of the group the circuit for relay G is maintained and this relay will eventually operate and connect at G9 the busy tone over wire T to the calling subscriber.

When relay E operated a circuit was completed for the switch R1 through E2, the interrupter springs and T1 to ground. This will cause the switch R1 to continue stepping until the relay T operates through wiper and bank contact 4, contacts HS4, and the hold wire H to the preceding finder. It will be understood that there is no more than one finder accessible to this control switch with a ground potential on the H wire. If this ground has not been applied when the switch R1 passes over the contacts particular to the predetermined conversation switch, due to the setting of the conversation switch at the preceding stage not being completed, the switch R1 will repeat its hunt. When relay T operates the obvious circuit is closed for the relief relay TT. TT1 and TT2 extend the subscriber's loop to relay A through the wipers and contacts of banks 1 and 2 thereby replacing the bye-pass over conductors + and -. Contacts TT3 remove the ground from the test wire causing the release of the previous control circuit. TT4 provides a locking circuit for the relay T and extends the ground to the hold wire to hold the previous switching relays. When both the relays TT and H are operated due to the fact that the switch R2 has found a free outlet in the required group and the switch R1 has found the finder which it has been predetermined will complete the call, a circuit is completed for the finder magnet S through bank contact and wiper 7, M3, TT7, H8 and at the same time a ground is extended through TT8 and the wiper and bank contact 9, to the finder wiper M and when the finder wipers stand on the outlet corresponding to that on which the switch R2 has switched through, the ground on the finder wiper M will be extended over the control wiper M1 or M2, J4 of J5, H13, to relay M. The operation of M opens the circuit for finder magnet S at M3 and closes the circuit for the relay G via E7, M2, the off-normal bank N2, E4, Q1, P1, TT6 to the ground on the test wire. Relay G will operate and close the circuit for relay HS through bank contact and wiper 6, G1, M4, TT7, H8, to ground. Relay HS will operate and HS6 will extend ground over the H wiper to the H wire of the succeeding finder in order to mark that switch to the succeeding control. Contacts HS2 and HS3 will prepare the permanent circuit to replace the bye-path. HS4 grounds the H wire to hold the previous switches independently of the control circuit. The control circuit does not release until the ground potential is removed from the T wire by the succeeding control circuit. When the relay H operated the circuit for relay A was opened and relay B released also after a short period. Relays E and T were maintained, over J2, H9, E13, or J3, H12, E14, however, by the ground potential on the test wire which is maintained by the succeeding control circuit under the control of the calling subscriber's loop. When the succeeding finder removes ground from the T wire, relays T and E release and subsequently relays TT, M and H release. When relay H releases, the homing circuit for the switch R1 is completed through E3, B3, H6, off normal contacts and wiper of bank 5, interrupter springs, T1, to ground. In a similar way the homing circuit for the switch R2 is completed through H7, M1, wiper and off normal contacts N2, E5, to ground. When both these switches have returned to their home positions the battery is reconnected to the test wire through B5.

Should it happen that the subscriber fails to dial, a circuit will be completed from ground on the pulse lead A through the home contact and wiper of the bank 8, E9, G5, B4, E6, to the relay G which will lock up to G4, C2, B1 to ground. After some predetermined period a second pulse will be received over the pulse wire B wiper and home contact of bank 10 of the switch R2, G2, to relay E. Relay E on operating will lock through E10 to ground at B1 and open the circuit for relay G at E6. Relay P will operate from ground at B1, through G7, H11, E14, wiper and home contact of the T13 bank to protective resistance and battery. Relay P will cause the operation of relay H and the subscriber's loop will be switched via H1 and H3, J6 and J8 through the home contacts of the banks -1 and +1, G8 and E1, back to the relay A. When relay E operated, it closed the driving circuit of the magnet R1, as already described and this switch will step forward until relay T operates. Relay T will close a circuit for the relay TT, which as already described closes a circuit for the finder magnet S. When the finder has been driven to the terminals corresponding to those on which the

switch R2 is standing (that is the home terminals), relay M will operate and a circuit will be closed for relay G through E7, M2, wiper and home contact of the bank N2, M4, 5 TT7 and H8 to ground. G1 closes a circuit for the relay HS which is maintained through HS6, H wiper and home contact of the finder S, home contact and negative wiper, HS2, subscriber's loop, HS3, positive wiper and 10 home contact, to ground. The operation of G8 opens the circuit for relay A which releases and opens the circuit for relay B. Relay B in turn opens the circuit for relays E, G, H and T causing the switch R1 to return to 15 normal. The finder relay HS is maintained operated over the subscriber's loop until the subscriber releases.

Referring now to the penultimate selector circuit shown in Fig. 4 a finder with its associated control circuit is tested in a similar manner to the second group selector circuit through BS1, GS3, TT3, TT5, P2, Q1, E12, wiper and home contact of the bank 10 of the 20 R1 switch, home contact and wiper of the bank C14 of the R2 switch, B6 to protective resistance and battery. If the finder and control circuit are found to be free, the preceding control circuit switches through the calling subscriber by means of the bye-pass 25 negative and positive wires thereby completing a circuit for relay A over H1. Relay A completes the obvious circuit for relay B and a stepping circuit for the magnet R1 similar 30 to that described for the absorbing and group selector circuits. The stepping of the switch R2 is completed through M1, the wiper and home contact of the bank N21, C1 and B1 to ground. When on the completion of dialling 35 the switch R2 reaches the commencement of the group, the circuit for relay E is completed 40 through G4, C3, M2, wiper and off normal contact of the bank N21, H5, E4 to ground. Relay E completes the testing circuits for relays P and Q at E14 and E15 respectively and 45 should a free outlet be available relay P and Q will close the circuits for relays H and J, as already described. When relay E operated a circuit was completed for the magnet R1 through E2, interrupter springs, T1 50 to ground causing the switch R1 to step until it swipes 4 is associated with the penultimate finder which it has been predetermined shall complete the connection. In this position a ground potential on the hold wire fed forward 55 from the preceding finder is extended to relay T which operates and closes the obvious circuit for relay TT. When both relays TT and H are operated due to the fact that the switch R2 has found a free outlet in the required 60 group and the switch R1 has found the finder A circuit is completed for the finder magnet S through the contact and wiper of bank 8, M4, E8, H6 and TT7 to ground, and at the same time a ground is extended 65 through TT8, the wiper and contact of bank

10, to the finder wiper M, and when the finder wipers stand on the outlet corresponding to that on which the switch R2 has switched through the ground on the finder wiper M will be extended to the control wiper 70 M14 or M24, J4 or J5, H8, to relay M and battery. The operation of relay M opens the circuit for the finder magnet S at M4 and places a ground potential via contacts M3, 75 the wiper and contact bank 7, BS8 on the H wiper of the penultimate finder. The penultimate control circuit remains in service while the last two digits are being received by the final selector circuit and the called line tested. 80 After the final selector circuit has completed the test, it removes ground from the test wiper T13 or T23 which was holding the penultimate control circuit causing relay E to release. A circuit is now completed for relay 85 GS through AS2, contact and wiper of bank 6, TT6, non-inductive resistance, E6, TT7, to ground. The non-inductive resistance is of such a value that the marginal relay BS will not operate in multiple with GS. It is possible, however, that the final finder has placed 90 a ground potential on the H wiper of the penultimate finder in which case it will be fed back through BS8, contact and wiper of bank 7, M3, E7, TT6, wiper and contact of bank 6 to relays GS and BS in which case 95 both relays will operate. The ground potential will only be placed on the H wiper by the final finder when the called subscriber's line is free as is explained later. The operation of relay GS will complete a circuit for 100 relay AS via GS1, DS1, subscriber's loop DS3, GS6. Relay A provides a holding ground for relay GS; relay BS in operating completes the ringing circuit through FS4, 105 BS7, called subscriber's loop BS4, FS2, the ringing tone battery RR. When the called subscriber answers, relay FS operates and completes a circuit for relay DS through FS1 and FS3. When the relay DS operates it reverses the direction of current in the called 110 subscriber's loop for metering purposes. Talking current is supplied to the calling and called parties through relays AS and DS respectively. DS6 provides a locking earth for 115 relay BS; the calling subscriber on releasing causes the relay AS and subsequently the relay GS to release and at GS6 remove the ground holding the preceding switches which are made to release. The penultimate finder will remain operated as long as the relay DS is held by the called subscriber. Relay BS which is held by relay DS prevents the penultimate finder being taken into use by opening contacts BS1. If the called subscriber 120 releases first relay DS makes the circuit of relay BS dependent upon relay GS and the called subscriber is held until the calling subscriber releases: during this time a signal is given via DS7 and FS6 to the supervisory 125 alarm over lead CSH. If the called sub- 130

scriber's line is engaged and relay GS operates without relay BS the busy tone lead BT is connected up at GS8 and BS5 to the calling subscriber. In either case GS5 opens the circuit for relay T which in turn opens the circuit for relay TT causing the release of the control circuit. If no outlets are found free by the control circuit, relay G will be operated over the following circuit:—B5, G2, 10 E10, M2, wiper and off normal contact of the bank N21, H5, E3, Q1, P2, TT5, B1 to ground. Relay G will extend ground from B1 through G5 and E5, non-inductive resistance, TT6, to wiper and contact of bank 6, to cause the operation of relay GS which will connect the busy tone circuit to the calling subscriber, as already explained. If the subscriber fails to dial on seizing the penultimate control circuit, the ground on the pulse wire A will 15 cause the operation of relay G through the home contact and wiper of bank 9, E9, G2, B5, to relay G. Subsequently the ground on the pulse wire B will operate relay E through the wiper and home contact of the bank N22, and 20 25 G3. With relays G and E operated ground from B1 is extended over G5 and E5, non-inductive resistance, TT6, wiper and contact of bank 6 to relay GS, applying a busy tone to the calling subscriber. It will be 30 seen that when relay H operates the negative wiper only is extended to the final finder the ground for the impulse circuit being maintained in the penultimate finder. An additional bank OM on the switch R2 is provided 35 for over-flow metering purposes and a ground potential is placed on the contact associated with the group required by G8 if there are not outlets available.

Referring now to Fig. 5 a final finder with 40 its associated control circuit is tested over the wire T, HS1, T3, wiper and home contact of the bank C5 of the switch R2, the home contact and wiper 9 of the switch R1, V6, B7, protective resistance to battery. The 45 negative wire is extended over the bye-pass to relay A which operates and operates relay B over the obvious circuit. When the first impulse commences a circuit is completed for the magnet R1, via T2, E3, B1, A2, to ground. At the same time a parallel 50 circuit is completed through B4 for the relay C. When the switch R1 steps into position 2 a circuit is completed for the magnet R2 through its interrupter springs P2, G3, the contact and wiper of bank 8 of the switch R1, H1, M2, G1, E2, B3 to ground. When the switch R2 reaches the position marked by the bank 9 of the switch R1, relay M will operate from ground at B5, over 55 V6 and B8 causing the circuit of the magnet R to be opened at M2. When the first digit is complete and relay C has released with relay M operated, a circuit is completed from ground, B3, E2, G1, M1, wiper and contact of bank 7 of the switch R1, C1, G5, to the relay G which operates. Relay G locks over at G6 through E6 to ground at B5. Relay G completes a circuit for the magnet R, through G4, strapped contacts in 60 positions 2 to 11 and wiper of bank 7, M1, 70 and interrupter springs to ground causing the switch R1 to take a step to its next position in which the circuit for relay M is opened and the driving circuit for magnet R1 replaced by G2, the strapped contacts in 75 position 2 to 11 and wiper of bank 8 of the switch R1, and H1 and M2. The switch R1 continues to be stepped by this circuit until it reaches position 12 where it awaits the units digit. The stepping for the units digit is similar to that described for the tens except that the switch R2 has no circuit until relay C releases the second time. The switch R2 then steps through P2, C2, contact and wiper of bank 8 of switch R1, H1, M2, 80 interrupter springs of the switch R1 to ground until relay M operates when the R2 switch is standing on a position marked by the R1 switch.

Relay M completes a circuit through the wiper and contact of bank 7 to the relay E which operates and locks through V1, E7, B5 to ground. Relay E opens the circuit for relay G at E6 but while G is releasing, this relay being of the slow to release type, a 90 testing circuit is completed from ground at H7, G9, TP1, E8, winding of relay P, J6 or J7 to the test wiper T25 or T15. Relay J is the discriminating relay and is operated when the R1 switch steps for the tens 95 digit on alternate contacts only of bank 1 of the switch R1 which are grounded. If the switch R1 is on one of these alternate positions when relay G operates, relay J will 100 remain operated through G8, J1, T3, B5 to ground. If relay J is not operated when relay G operates it will have no further opportunity. If the line called is free relay P will operate and close the obvious circuit for relay H. When relay G releases a circuit 105 is completed for the magnet R1, through T2, E1, G1 and the interrupter springs to ground. This stepping will continue until the relay T operates through E5, the wiper and contact of bank 2, and HS3 to the hold 110 wire of the final finder which has been predetermined by the penultimate selector circuit. The ground at the interrupter springs of magnet R1 is then extended through G1, E1, T1, H6 and M4 to the wiper and contact of bank 4 and final finder magnet S. At 115 the same time relay M is extended through B8, V6, wiper and bank contact 9, to the marking wiper M of the final finder. When the final finder wiper stands on the outlet 120 corresponding to that on which the R2 switch is standing, relay M is extended to the marking wiper M25 or M15 of the switch R2, J4 or J5, H8 to ground. Relay M opens 125 at M4 the circuit for the final finder magnet 130

S and closes the circuit at M3 through wiper and contact of bank 3 for relay HS which locks through HS4 to the test wire which is grounded from B5 over H9, J6 or J7, and wiper T25 or T15. HS1 opens the bye-path test which releases the penultimate control and HS2 places the ground potential on the H wire causing the operation of relay BS in the penultimate finder. If the called subscriber's line is engaged, relay P will not operate and when relay G releases the circuit for relay P is opened. The stepping circuit for the magnet R1 is closed at G1, as already described, and when relay T operates ground on the bye-path test wire is removed at T3; T4 provides a locking circuit for relay T. In this case there is no ground on the hold wire H and when the penultimate control releases relay GS only will operate. Should it happen that the line tested is the first of a P. B. X. group and relay P does not operate, a circuit is completed from battery and protective resistance on the contact of the bank X1 or X2, J2, or J3, E9, V2, winding of the relay V, G10, H5, B5 to ground. Relay V locks at V3 over a protective resistance to battery and opens at V1 the locking circuit for relay E which releases and replaces the circuit for relay G at E6. The circuit of relay M is switched over by V5, J2 or J3 to the P. B. X. discriminating terminals and the circuit for the magnet R2 is connected due to the fact that relay M releases. At each step forward a testing circuit is provided for relay P through V4 to ground at B5. When an idle line is engaged relays P and H energize and a circuit is closed over H10 for relay E, which opens the circuit of relay G and closes the circuit for driving the switch R1. The switch R1 trunks for the predetermined conversation switch and the operation continues as before. On the last line of a group, if relay P has not already operated, ground from the discriminating bank X1 or X2 causes the operation of relay M which opens the driving circuit of the magnet R2 and causes the re-operation of relay E. Relay G will release after a period opening the circuit for relay V at G10. Due to the fact that relay H has not operated when relay T operates, the busy signal is passed back to the penultimate finder. Should it happen that the subscriber fails to dial a pulse circuit is completed for the two-step relay TP, via B9, C3, TP4, E10 and the pulse wire TP, and at the end of the pulse, relay TP will be locked up over its light contacts TP2. When the second time pulse is received it will cause the operation of relay E through V1, TP3, and E10. Relay E will lock to E7 and B5 to ground. Relay E closes a circuit for magnet R1 and when relay T operates as already described, the busy signal is passed back to the penultimate finder. On the release of the

control circuit of the penultimate finder the circuit for relay A of the final control circuit is opened and relay A opens the circuit for relay B which closes the restoring circuits of the two magnets R1 and R2. The restoring circuit for the magnet R1 extends via T2, E8, B2, and the off-normal bank 6, whilst that for the magnet R2 extends via the off-normal bank N2 and B5. If the number dialled is one of a P. B. X. but not the first line, automatic hunting will not take place due to the fact that the battery potential is only connected to the first line of the group. The cross connection between the bank C of the switch R2 and the bank 9 of the switch R1 is such that consecutively numbered lines may both be P. B. X. groups or more than one line due to the fact that the switch R2 steps round until it reaches the position marked by the switch R1.

Common spark-quenching condenser and resistances for the driving magnets S of the conversation switches at each numerical selecting stage are located in the control circuits.

The operation of the modified selector circuit illustrated in Figure 6 will now be described. As illustrated this selector circuit can be substituted in the system previously described in place of the selector circuit shown in Figure 3.

The selector circuit with its associated control switch is tested through the wire T, contacts HS1, TT3, TT6, P2, Q1, E9, the wiper and home contact of the bank 10 of the switch R1, home contact and wiper AC of the switch R2, B7, the home contact and wiper of the bank BC of the switch R3, B4, to resistance and battery. If this resistance and battery is connected to the test wire the previous control switch will be able to switch through in the manner described in the call already followed out, extending the subscriber's loop to BP+ and BP- thereby causing the operation of relay A through H6 and H7. Relay A closes the obvious circuit for relay B through A2, and relay B places ground on the test wire at B1 and removes battery from the test wire at B7 and B4. At B6 a circuit is closed for relay M from battery and winding of relay M, D9, H13, B6, wiper and home contact of the bank AC, home contact and wiper of the bank 10, E9, Q1, P2, TT6, B1 to ground. At the first impulse relay A releases but relay B being of the slow release type remains operated and completes the circuit for the magnet R1 through E1, B3, winding of relay C, A1 to ground. At the end of the impulse relay A reoperates and the switch R1 steps into position 2. Relay C is also of the slow release type and remains operated during the series of impulses. Relay C also closes the following circuit for the magnet R2, through its interrupter springs, D4, the wiper and home contact of the bank N2, C2, Q1, P2,

TT6, B1, to ground. The switch R2 opens its own circuit when it steps off normal. When the switch R1 steps into position 2 at the end of the first impulse the circuit for relay M 5 is opened by the wiper 10 and when relay M releases the circuit for the magnet R2 is again completed through the off normal contact of the bank M2, M2, H3, E4 to ground. The switch R2 continues stepping by means 10 of its own interrupter springs until relay M reoperates. The switch R1 takes one step for each impulse received from the subscriber's dial and the strapping between the banks 10 and AC is so arranged that the circuit for relay M is completed whenever the switch R2 reaches the commencement of the group corresponding to that on which the switch R1 is standing. The switch R2 has 15 access to 100 outlets which will serve a number of groups which are themselves differentiated by the setting of the switch R1 in response to the dialled impulses. Other groups are reached by the banks of the switch R3 and a discriminating relay D is provided 20 to operate when the switch R1 reaches the first group connected to the switch R3. This circuit may be traced from battery, winding of relay D, D5, wiper and bank contact 10 of the switch R1, E9, Q1, P2, TT6, B1 to ground. Relay D locks through D6 to ground at B1. If relay D is caused to operate the circuit for relay M is transferred through 25 D10, H15, and B5 to the bank BC of the switch R3 and the commoning between the bank 10 of the switch R1 and the bank BC is so arranged that the circuit for relay M is completed whenever the switch R3 reaches the commencement of the group corresponding to that in which the switch R1 is standing. The driving circuit of the switch R3 30 extends over the interrupter contacts, D3, off-normal bank N2, M2, H3, E4, and after the switch has moved a step, over its off-normal bank N3. When the digit is completed 35 relay C will release after a period and when relay M operates due to the switch R2 or R3 having reached the position indicated by the bank 10, a circuit will be completed for relay E from battery and winding of relay E, C1, M1, H3, E4, to ground. Relay E will 40 close its light contact E5 and lock over its second winding to ground at B1. E9 opens the circuit for relay M which releases and recloses the driving circuit of the switch R2 45 or R3 through M2, H3, E3, Q1, P2, TT6, to ground at B1. Contacts E7 and E8 close the testing circuit for relays Q and P respectively and one or both of these relays 50 will operate if the outlets on which the wipers are resting are free. If relay P alone operates, the driving circuit of the switch will be opened at P2, at P1 a circuit will be closed for relay H which will lock up through H1, 55 and TT6, to ground at B1. If relay Q operates, the driving circuit of the switch will be 60 opened at Q1, at Q2 a circuit will be closed for relay J which will operate and close at J1 a circuit for relay H which will also operate. If all the outlets of the group are engaged the switch R2 or R3 will step eventually to the last contacts of the group in which position a circuit will be closed for relay M through D9 or D10, H13 or H15, B6 or B5, 65 wiper and bank contact AC or BC, E10, Q1, P2, TT6, B1 to ground. Relay M will open 70 the driving circuit of the switch at M2 and close at M1 a circuit for relay G. Relay G is of the slow to operate type and will not operate during the period when relay M is operated and relay C normal, during the 75 initial operation of the former. However, at the last contact of the group the circuit for relay G is maintained and this relay will eventually operate and connect at G3 the 80 busy tone to the calling subscriber over lead BT. When relay E operated a circuit was completed for the switch R1 through E2, interrupter springs T1 to ground. This will cause the switch R1 to continue stepping until the relay T operates through the wiper 85 3, contacts HS2 and the hold wire H to the preceding selector. It will be understood that there is only one idle selector accessible to this control switch with a ground potential on the H wire at this time. When relay T 90 operates the obvious circuit is closed for the relief relay TT. TT1 and TT2 extends the subscriber's loop through relay A over the wipers and contacts of banks 1 and 2 of the switch R1 and thereby replace the bye-path. TT3 removes the ground from the test wire 95 causing the release of the previous control switch; TT4 provides a locking circuit for the relay T and extends ground to the hold wire H to hold the switching relays of the preceding switches. When both the relays 100 TT and H are operated due to the fact that the switch R2 and R3 has found a free outlet in the required group and the switch R1 has found the selector which it had been pre-determined will complete the call, a circuit 105 is completed for the selector magnet SB via H4, TT7, F2 and bank 7 of the switch R1 and if the relay D is not operated, for the selector magnet SA also via D2, M4 and the bank 6. 110 If the discriminating relay D has been operated, the bye-path has been established by the switch R3 and the connection will be established by the switch SB of the selector. In this case the magnet SB will cause its 115 wipers -B, +B, HB and MB to step until the following circuit is established:—battery and winding of relay F, D18, H16, J6 or J7, wiper and bank contact of the bank BM2 or BM1, multiple wire to the contact and wiper MB of the selector, bank contact and wiper of bank 10 of the switch R1, TT8, Q1, P2, TT5 to ground. Relay F in operating completes the circuit for relay HS via F1, D1, 120 TT7, H4. 125

130

If the discriminating relay D was not operated both the magnets SA and SB would cause their wipers to rotate. The circuit for the magnet SB will be opened by the operation of relay F which is connected through D17 to a certain predetermined bank contact of the bank MB of the switch B6 and the circuit for the magnet SA will be opened by the operation of relay M through D9, H14, J4 or J5, the wiper and bank contact of the bank AM1 or AM2, multiple wiring to the bank contact and wiper of bank MA of the selector, bank contact and wiper 9 of the switch R1, TT8, Q1, P2, T5, to ground. The wipers of the switch A6 may be connected to two, three or more predetermined positions of the switch B6 to reduce the hunting time of this switch: in this case corresponding contacts in the bank MB will be connected to the relay F. When both the relays M and F are operated the circuit is completed for the relay HS through bank contact and wiper of bank 4 of the switch R1, F1, M3, D2, TT7, H4 to ground. Relay HS in operating will extend ground over the hold wire from HS3 to the preceding selector and extend ground over HS6 to the hold wire of the succeeding selector. Contacts HS4 and HS5 will prepare the permanent circuit to replace the bye-path. If the circuit is being extended by the switch A6 of the selector the conductors will be extended through the wipers and a predetermined bank contact set of the switch B6. It will be seen, that when the two sets of wipers are rotating simultaneously there is no possibility of two sets of outlets being connected together by the wipers. Furthermore, if the call is being extended by the switch B6 the position of the switch A6 is immaterial and this switch may therefore be left in any position in which it may be standing. The control switch does not release until the ground potential over the test wire is removed by the succeeding control switch. When the relay H operated the circuit for relay A was opened and relay B6 released also after a short period. Relays E and T were maintained, however, by the ground potential on the test wire which is applied by the succeeding control switch under the control of the calling subscriber's loop. When the succeeding selector removed ground on the test wire relays T and E release and subsequently relays TT, M and H release. When relay H releases the homing circuit for the switch R1 is completed through E1, B2, H2, off normal contact and wiper of the bank N1, interrupter springs, to ground at T1. In a similar way the homing circuit for the switch R2 is completed through D4, the off normal contacts N2, M2, H3, E4 to ground and the circuit for the switch R3 through the off normal contacts N3, M2, H3, E4 to ground. When both these switches have returned to their home positions the battery is connected to the test

wire. The magnets R1, R2 and R3 are each provided with their own spark quenching combination consisting of a condenser and resistance, and a common spark quenching combination is provided for all the SA magnets associated with the control circuit and in a similar way an additional condenser and resistance is provided for the magnets SB: these are associated over the banks 5 and 8 of the switch R1.

It will be understood that this arrangement is not limited to two permanently associated switches and that if the number of groups of outlets is sufficient a further switch R4 may be added to the control circuit which will operate under the control of a further discriminating relay similar to D and a further switch (c) will be added to the selector circuit and connected through a predetermined position or positions on the bank 85 of the switch A.

Reference will now be made to Fig. 7 which shows a method whereby a group of conversation switches may be switched from a faulty control circuit to an adjacent control circuit which normally serves a different group of conversation finder switches. The figure illustrates sufficient of the circuit of two control circuits C1 and C2 and certain of their associated conversational finder switches for a complete understanding of the arrangement. Two conversation finders 1 and 2 of the group of, say ten conversation finders associated with the control circuit C1, and one conversation finder 20 of the group associated with the control circuit C2, are shown. BP1 represents the wipers of the bye-passing switch associated with the control circuit C1, and BP2 the wipers of the bye-passing switch associated with the control circuit C2. Each conversation finder is provided with an attaching relay KS1, KS2, or KS20 holding relay HS1, HS2, or HS20, and stepping magnet S1, S2 or S20. Three multiple wires extending from the control circuits and adapted to be operatively associated with the talking group finder over contacts of the KS relays are shown.

As already fully explained it is the function of a control circuit to receive the dialled impulses and cause its bye-pass switch to select an idle or wanted line. The relay H (or H1) is then operated and the connection extended to the wipers of this switch, as already described. Relay H (or H1) applied a marking potential to a marking contact of the selected trunk over the winding or test relay M (or M1) and front contacts 1 of relay H (or H1) connects an opposite potential to the control wiper M of the conversation finder switch over front contacts 3 of relay H (or H1), back contacts of a relay QQ1 (or QQ2) and front contacts of relay KS1, (or KS2 or KS20), and closes a stepping circuit for the magnet SL (or S2 or S20).

of the conversation finder over back contacts of relay M (or M1), front contacts 2 of relay H (or H1), back contacts of relay QQ1 (or QQ2) and front contacts of relay KS1 (or KS2 or KS20). When the conversation finder switch reaches the marked trunk, test relay M (or M1) energizes and opens the stepping circuit of the S magnet. The control circuit is detached subsequently as previously described.

The control circuits are paired and arrangements are made whereby each control circuit of a pair acts as a reserve for the other. For this purpose each control circuit C1 or C2 is provided with a change-over relay QQ1 or QQ2 which when energized switches over the multiple wires from its own control circuit to the other. The circuit of this relay QQ1 or QQ2 may be completed manually by throwing a change-over key QK or the relay may be automatically energized by causing a faulty relay (not shown) to earth the wire F.

It will be apparent that if mutual operation is to be arranged between the two control circuits, the marking contacts of the bypass must be multiplied over all the conversation finders of the two groups, and to ensure that there will be no confusion when both control circuits are operative, the marking condition must be such that the test relay M or M1 of one control circuit will not operate due to a marking potential from the other control circuit. On this account, relay M is connected to battery and the associated selectors search for a battery potential, whereas relay M1 is connected to ground and the associated conversation finder switches search for an earth potential.

As both bye-pass switching cannot seize the same trunk there is no danger of both potentials being placed on the same terminal. For the same reason there is no possibility of the two test relays M and M1 being energized in series.

As an alternative arrangement the test relays M, M1 may be placed in the control circuit in the leads which are extended to the conversation finder switch marking wipers. In this case as it is possible for both conversation finders switch wipers to rest on contacts belonging to the same outlet the test relays must be designed not to operate in series.

To apply this feature to the circuits shown in Fig. 2 for example, the wipers of the switch R1 are arranged to give access to conversation finders of two groups, viz., those of the group to which the finder illustrated belongs, and in later positions to finder of an adjacent group normally served by another control circuit. The wiper 2, Fig. 2 searches over the positions allotted to that group to which the finder shown belongs, but if the control circuit normally serving the

other groups becomes faulty a relay such as QQ1, Fig. 7, connects to the wiper 2 an additional wiper 1 (over contacts QQ) which is arranged to search over the finders of this other group. In this manner the control circuit shown is made to serve the two groups of finders.

I claim:

1. In a telephone system, the combination of a plurality of conversation switches, a control switch, means for operating said control switch in response to impulses to hunt for a predetermined conversation switch and for marking said switch.

2. In a telephone system, a plurality of switching stages, a plurality of conversation switches at each switching stage, control circuits associated with said plurality of conversation switches at each switching stage, a bypass circuit extending from one switching stage to another, and means under control of said control circuits at one switching stage whereby an idle conversation switch and a control circuit at the second switching stage are taken in use over said bypass circuit extending from a control circuit which has been selected for use with a conversation switch at the preceding switching stage.

3. In a telephone system, the combination of a plurality of switching stages, conversation switches at each switching stage, control circuits, associated with conversation switches at each switching stage, a test conductor for testing a conversation switch associated with an idle control circuit at one switching stage, and means for subsequently transmitting a signal back over said test conductor from the succeeding switching stage.

4. In a telephone exchange system, the combination of an automatic switch having a group of outlets, an auxiliary switch of the single motion type which responds to digit impulses, means for transmitting such impulses to said auxiliary switch, means according to the value of the first digit received by said auxiliary switch to cause the advance of said automatic switch to a wanted group of outlets or to control the advance of the auxiliary switch to a predetermined intermediate position, means in response to a second digit impulse to thereafter advance the automatic switch to a group of outlets determined by the second digit.

5. In a telephone exchange system, two permanently associated switches provided with wipers, the wipers of one switch being directly connected to wipers of the other and the wipers of the other connected to a particular set of bank contacts of said first switch, and means provided for advancing said first switch alone or for simultaneously advancing both of said switches.

6. A telephone system comprising a plurality of switching stages, each stage having a plurality of conversation switches, control

circuits individual to each stage and adapted to be associated with any one of the conversation switches in that stage and a by-path conductor extending from a control circuit 5 at one switching stage, an idle conversation switch and an idle control circuit at a succeeding stage being adapted to be taken into use over said by-path conductor.

7. A telephone system comprising a plurality of conversation switches, a control circuit comprising first and second switches and adapted to be associated with any one of said conversation switches, said first switch being adapted to hunt for an idle conversation 10 switch and to control the selective operation of said second switch.

8. A system according to claim 7 wherein said second switch is adapted to control the selective operation of the idle conversation 15 switch.

9. A telephone system comprising line 20 finder switches and selector switches over which a talking circuit is adapted to be completed, all of said switches being of the non-homing type and having motion in one plane only.

10. A telephone system comprising a subscriber's station, a control office, a plurality of switching stages at said office, a transmission 25 bridge at one of said switching stages, and a direct metallic circuit extending from the subscriber's station to a switching stage following that at which said transmission bridge is located.

11. A telephone system comprising a plurality of switching stages each stage having a plurality of conversation switches, control 30 circuits individual to each stage and adapted to be associated with any one of the conversation switches belonging to that stage, a control switch associated with one of said control circuits, means for transmitting digit impulses of various values to said control switch and means under the control of said control 35 circuit for absorbing a digit of a particular value.

12. A telephone system comprising two permanently associated switches having access to different groups of lines, means for 40 advancing one of said switches or for simultaneously advancing both switches according to the group of lines to which a line to be selected belongs.

13. A telephone system comprising two 45 groups of conversation switches, control circuits individual to each of said groups adapted to control the operation of the switches therein, and means to disassociate a switch in one group from a control circuit of that 50 group and to associate said switch with a control circuit belonging to the other group.

14. A telephone system comprising two 55 groups of conversation switches, control circuits normally adapted to be associated with 60 and to control the selective operation of the

switches in one group, control circuits normally adapted to be associated with and to control the selective operation of the switches of the other group and means whereby any one of said control circuits may be made 70 available to any one of said switches.

In witness whereof I hereunto subscribe my name this twentieth day of June, 1929.

ESMOND PHILIP GOODWIN WRIGHT.

DISCLAIMER

1,858,069.—*Esmond Philip Goodwin Wright, Aldwych, London, England. AUTOMATIC TELEPHONE EXCHANGE SYSTEM. Patent dated May 10, 1932. Disclaimer filed April 6, 1933, by the assignee, International Standard Electric Corporation.*

Hereby enters this disclaimer to claim 10 of said patent, which is in the following words to wit:

“10. A telephone system comprising a subscriber's station, a control office, a plurality of switching stages at said office, a transmission bridge at one of said switching stages, and a direct metallic circuit extending from the subscriber's station to a switching stage following that at which said transmission bridge is located.”
